AIR DELIVERY CONTAINER

Arthur B. Schultz, Wilmington, Del., assignor to
All American Airways, Inc., a corporation of
Delaware

Application April 23, 1945, Serial No. 589,813

8 Claims. (Cl. 244—138)

1

This invention relates to containers employed in air delivery service and is concerned primarily with a container that is designed for handling delicate and fragile cargo.

At the present time air pick-up and delivery service is becoming more and more widespread in its use and with the termination of the war it is believed that this service will be greatly expanded in the commercial fields. From the very nature of the service, cargo is delivered from a flying plane to the point of delivery without interrupting the flight of the plane. This means that the cargo is thrown off or dropped from the moving aircraft.

While many types of cargo will withstand such rough handling, there are obviously many other kinds of a more delicate and fragile nature which would be greatly damaged, if not completely destroyed, if delivered in this manner by the presently available equipment.

With these conditions in mind that invention has in view as its foremost objective the provision, in air delivery equipment, of a container designed to receive and handle delicate and fragile cargo without injury or damage. In providing a cargo container of this type the invention proposes no change or departure from the present practice of throwing out the container. What the invention does provide is a container which accommodates or takes up the shock created by impact with the ground or by sudden opening of the parachute.

A further object of the invention is the provision, in air delivery equipment, of a cargo container comprising an outer casing, an inner casing, and means for absorbing energy as an incident to relative movement between the casings. In carrying out this idea in a practical embodiment the outer casing is designed with a uniform cross section and is hollow therethroughout. The inner casing is snugly fitted within the outer casing for sliding movement and is normally held in a suspended position at the top of the outer casing by strands of a synthetic plastic in an un-drawn state which have the ability of absorbing energy as they are being drawn. Thus, when the lower end of the outer casing strikes the ground the inner casing continues its downward movement which is gradually decelerated by the un-drawn synthetic plastic suspension means.

A further object of this invention is the provision, in delivery equipment of the character above identified, of replaceable means for suspending the inner casing within the outer casing. This means may take the form of the synthetic

2

plastic strands above referred to and any attaching devices which may be associated therewith.

In order for a cargo container of the character above indicated to function properly it is essential that the lower end of the outer casing strike the ground upon completion of the descent. This means that the container should assume and remain in a substantially vertical position as it falls. Accordingly, a further somewhat more detailed object is the provision, in air delivery equipment of the character indicated, of a stabilizing means for maintaining a container in substantially vertical position as it descends to the earth.

15 In carrying out this idea in a practical embodiment, two alternatives immediately suggest themselves. One of these is to employ a small drogue which is anchored to the upper portion of the outer casing, or the outer casing might be provided with fins which would cooperate with the air in maintaining the vertical position.

Under some conditions it might be desirable to provide on the bottom of the container a shock absorbing element in the form of a small bumper. In view of this requirement a further object is the provision, in air delivery equipment, of a container for delicate cargo which includes at its impact end a bumper.

When a drogue is employed to maintain the vertical position this end is accomplished but it still must be remembered that under many conditions appreciable cross winds exist and lateral components of movement are imparted to the container. In view of this condition, a further object of the invention is the provision, in air delivery equipment, of a cargo container including a drogue for maintaining the container in a substantially vertical position together with a grappling element or anchor which is carried at the end of a line that is secured to the connection between the drogue and the container. This anchor will first engage the ground and become effective against the effects of cross winds to cause the lower end of the cargo container to engage the ground in the manner desired.

Various other more detailed objects and advantages of the invention such as arise in connection with carrying out the above noted thoughts in a practical embodiment will in part become apparent and in part be hereinafter stated as a description of the invention proceeds.

The invention, therefore, comprises a container for delicate and fragile cargo which is designed for use in air delivery and which consists of an outer casing which encloses an inner casing which

is movable therewithin and which is normally suspended within the outer casing by undrawn synthetic plastic strands which will absorb energy as they are drawn. The stabilizing means which may take the form of a drogue is included to assure the container's remaining in a substantially vertical position during descent and a ground engaging grapple or anchor is included in the assembly to assure proper engagement of the lower end of the container with the ground under prevailing conditions of cross winds.

For a full and more complete understanding of the invention reference may be had to the following description and accompanying drawings wherein:

Fig. 1 is a side view taken as a vertical section through the container with the drogue shown in elevation,

Fig. 2 is a view in side elevation of a slight modification, and

Fig. 3 is another side view showing the assembly as including a ground engaging grapple. In this view different positions of the container are depicted by dotted lines.

Referring now to the drawings wherein like reference characters denote corresponding parts and first more particularly to Fig. 1, a container for delicate cargo is referred to in its entirety by the reference character C. The container C comprises an outer casing 10 which is preferably cylindrical in shape. At the bottom the casing 10 is closed by a bottom closure 11 which may have the property of removability incorporated by the U-shaped flange construction at 12. The upper end is similarly closed by top closure 13 which is secured to the cylindrical wall by U-shaped flange construction corresponding to that shown at 12.

The cylindrical casing 10 may be made from any material desired although the invention has particularly in mind the use of some cheap material which might be considered as expendable. Cardboard or fiber board are good examples of such material.

Extending into the interior of outer casing 10 and securely anchored thereto are a plurality of headed studs 14 for a purpose to be later described. The number of these studs may be varied within a fairly wide range depending upon the particular conditions of usage to which the container is to be subjected.

An inner casing 15 has a shape corresponding to the outer casing 10. Thus it is also cylindrical in formation as it is adapted to have free sliding motion within the outer casing 10. Mounted on the exterior of casing 15 adjacent to the lower end thereof are a plurality of headed studs 16 which correspond to the studs 14.

Replaceable means for suspending the inner casing 15 within the outer casing 10 is shown in the form of a strand 17 which is inter-laced over the studs 14 and 16 to hold the inner casing 15 in a suspended position in the upper portion of the outer casing 10. The nature and properties of this strand 17 is a particularly important part of the invention. The strand 17 is made from filaments of an undrawn synthetic plastic which has the ability of absorbing energy as it is being drawn. Examples of such synthetic plastic are nylon, polyethylene, Vynylon, and Vinylite. Regardless of which material is employed it should if necessary be treated so that it retains this ability to absorb energy as it is drawn. The strand 17 should be susceptible of at least 100% elongation during drawing and with certain of

the materials above noted, particularly undrawn nylon, this percentage will be greatly exceeded.

A drogue is designated generally D and comprises a canopy 18 formed with an opening 19 at 5 the top of which canopy is connected to the outer casing 10 by lines 20.

While the operation and mode of usage of the above described container for delicate cargo is believed to be obvious, it may be briefly outlined 10 by noting that the top closure 13 is first removed to obtain access to the interior of the container. The delicate or fragile cargo is now placed within the inner casing 15 and the strand 17 is, of course, properly adjusted to suspend the container 15 in 15 the upper portion of the outer casing 10. Top closure 13 is now replaced and the container is now ready for delivery.

When it is thrown from an aircraft the drogue 20 D functions as a drag and serves to maintain the container in a substantially vertical position. Thus at the moment of impact with the ground the lower end of the casing 10 first engages the ground. However, the inner casing 15 continues its downward movement which is resisted by the 25 tendency of the strands 17 to resist drawing. Thus, further downward movement of the inner casing 15 subsequent to impact with the ground is gradually decelerated. Fig. 1 shows in dotted lines an intermediate position of the casing 15 30 after the strand 17 has been partially drawn.

Referring now more particularly to Fig. 2 it will be noted that the bottom closure 11 is provided with a shock absorbing element in the form of a bumper 21. This serves to take up part of the 35 initial impact with the ground.

Referring now to Fig. 3 it will be noted that the container C is connected to the drogue D by a slightly different form of connection. In this embodiment of the invention the lines 20 of the 40 drogue are gathered in an eye 22 which is carried by a connection 23 projecting upwardly from the top closure 13. An anchor line 24 is also connected to the eye 22 and at its lower end carries a ground engaging anchor or grapple 25. The form 45 of the invention shown in Fig. 3 is particularly adapted for use under conditions when strong cross winds prevail. Thus the container C with the drogue D will remain in a vertical position while the cross winds create a lateral component 50 of movement. In the absence of the anchor 25 this might result in serious damage to the container and cargo therewithin as the lower end of the outer casing 10 would not strike the ground with a downward vertical impact.

55 However, Fig. 3 shows the effectiveness of the anchor 25. It first engages the ground and remains fixed at the point of engagement. This gradually changes the path of the container C as it travels from the straight line resultant of 60 its lateral and downward components to a circular movement which terminates as the lower end of the casing 10 engages the ground under conditions comparable to straight vertical impact.

While preferred specific embodiments of the 65 invention are hereinbefore set forth, it is to be clearly understood that the invention is not to be limited to the exact constructions illustrated and described because various modifications of these details may be provided in putting the invention 70 into practice within the purview of the appended claims.

What is claimed is:

1. In delivery equipment of the character described, a container for delicate cargo comprising 75 an outer casing, an inner casing adapted for

movement within said outer casing, and an undrawn synthetic plastic filament having the ability to absorb energy as it is being drawn, suspending said inner casing in the upper portion of said outer casing.

2. In air delivery equipment, a container for delicate cargo of the character described comprising an outer casing, an inner casing adapted for movement within said outer casing, and an undrawn nylon strand holding said inner casing in a suspended position in the upper portion of said outer casing.

3. In delivery equipment, a container for delicate cargo of the character described comprising an outer casing, an inner casing adapted for movement within said outer casing, and an undrawn polyethylene strand holding said inner casing in a suspended position in the upper portion of said outer casing.

4. In air delivery equipment, a container for delicate cargo of the character described comprising an outer casing, an inner casing adapted for movement within said outer casing, and an undrawn Vynylon strand holding said inner casing in a suspended position in the upper portion of said outer casing.

5. In delivery equipment, a non-separable cargo container of the character described comprising a cylindrical outer casing, a cylindrical closed inner casing, means for holding said inner casing enclosed in said outer casing in a suspended position in the upper portion of the said outer casing and which means is capable of absorbing energy as said inner casing moves within the said outer casing, and a drogue connected to said outer casing.

6. In air delivery equipment, a non-separable cargo container of the character described comprising relatively movable inner and outer casings, means permanently suspending said inner casing completely enclosed within said outer casing until removed manually which means resists said relative movement, a drogue connected to the upper end of said outer casing,

and a ground engaging anchor connected by a line to said container.

7. In air delivery equipment, a container for delicate cargo comprising an outer cylindrical casing, an inner cylindrical casing adapted for movement within said outer casing, a strand of undrawn synthetic plastic holding said inner casing in a suspended position in the upper part of said outer casing, said strand having the ability to absorb energy as it is being drawn, a drogue, a connection between said drogue and the upper part of said outer casing, a ground engaging anchor, and a line connected at one end to said anchor and at the other end to said connection between said drogue and said outer casing.

8. In air delivery equipment, a container for delicate cargo comprising an outer cylindrical casing, an inner cylindrical casing adapted for movement within said outer casing, a strand of undrawn synthetic plastic holding said inner casing in a suspended position in the upper part of said outer casing, said strand having the ability to absorb energy as it is being drawn, a drogue, a connection between said drogue and the upper part of said outer casing, a ground engaging anchor, and means for operatively connecting said anchor to said container and drogue.
